DESIGN FOR A BENCH OR SIMILAR ARTICLE

Michael G. Marrone, Fitchburg, Mass.

Application March 23, 1942, Serial No. 106,280

Term of patent 3½ years

To all whom it may concern:

Be it known that I, Michael G. Marrone, a citizen of the United States, residing at Fitchburg, in the county of Worcester and State of Massachusetts, have invented a new, original, and ornamental Design for a Bench or Similar Article, of which the following is a specification, reference being had to the accompanying drawing, forming part thereof.

The figure is a perspective view of a bench or similar article, showing my new design. The design is the same on the opposite end.

I claim:

The ornamental design for a bench or similar article, as shown and described.

MICHAEL G. MARRONE.
